John J. Flannery Chambersburg Pa.

Cotton Patent

The following is to the full Cotton Patent and making part of the same containing a description in the words of the inventor of my improvement in the construction of granaries for protecting & preserving wheat & other grain from the attacks of the insect commonly denominated weevils.

I call to the world the present shall come as it has been the desire of the inventor Chambersburg in the County of Franklin and State of Pennsylvania to make known a new and useful improvement in the constructing Granaries for protecting & preserving wheat & other grain from the attacks of the insect commonly denominated weevils and that the following is a full and exact description of the construction of the same as invented or improved by me. My improvement consists in introducing a hot fire or Sleep fire either under or long close to a suitable room or apartment into which the grain is to be put and I have found by repeated experiment that the effluvia of the fire or smoke such cause operate as a complete protection against the attacks of the weevil also should the grain be infested by them to have deposited they will quickly leave it; thus leaving the farmer by his very simple contrivance against the ravages of an enemy who has been known to destroy whole crops in a few weeks and that too often he has incurred all the expense and trouble of transposing it from the field to the stack, & I also apply my improvement to grain in the stacks by constructing a fire under the stack in a similar manner to have it to grain necessary. Although there are many ways in which my granary may be constructed I deem it incumbent on me to describe that which I prefer. When four or more posts either set in the ground or resting on a proper foundation in an upright position I construct a house with proper doors for introducing the grain weather sealed and floored sufficiently tight to prevent the grain from piping out and to exclude the rain. The roof should project several feet on each side to shelter certain holes or openings for the admission of fresh air under the eaves. The floor should be raised a convenient height from the ground say to a foot and the eaves post at least should be in one piece reaching

1045

from the ground to the top of the house suitable timber floor resting on steps
so as to raise it from the ground is next to be laid for the granary steps, and between
these by planks secured to the posts by which the sides of the pen are formed, the
grainery constituting a roof to shelter it from sun and rain. The upright posts
that sustain the house are each to be covered with a sheet of tin lapped round
them just under the floor and secured by nailing or any other means in common
use resorted to for the purpose of preventing the rats &c from climbing up. There
is to be a platform or roof strongly supported by railing
above the pen or step and the grain stacked upon it instead of the ground. The
post I claim is new and as my invention a device for which I ask Letters
Patent is the combination of a hog pen or sheep pen with the grainery as herein
set forth whereby the horses can enter & pass over it to prevent from attacking
the grain. In Testimony that the foregoing is the specification of my said in-
vention I have hereunto set my hand this twenty-first day of July 1855
